AUTOMATIC AMPERAGE FEED CONTROL
MECHANISM

Clarence J. Hess, Shade Gap, Pa.

Application June 16, 1934, Serial No. 731,002

9 Claims. (Cl. 172—239)

- This invention relates to feed control mechanism, and more particularly to a device for controlling the rate of feed to a mill such as a flour or feed mill or the like.
- 5 One object of the invention is to provide a device for controlling the rate of feed in accordance with the load upon the mill.
- Another object of the invention resides in a device for preventing initiation of the feed until 10 the mill is brought up to speed.
- Another object of the invention is to provide an electrically driven mill and feed mechanism in which the rate of feed is automatically controlled in accordance with the electrical load 15 taken by the driving motor.
- Another object of the invention is to provide a feed control mechanism for maintaining the load current taken by the mill driving motor substantially constant by regulating the rate of 20 feed.
- Another object of the invention is to provide a device for automatically and immediately stopping the feeding mechanism whenever the mill driving motor is disconnected from its source of 25 power.
- A further object of the invention is to provide a time delay device to initiate the operation of the feeding mechanism at a predetermined time after the mill driving motor has been connected 30 to its source of power.
- A still further object of the invention is to provide a friction clutch between a driving motor and the feed mechanism and electrically actuated means responsive to the load on the 35 mill for causing the clutch to slip in the event of an overload.
- Other objects and advantages of the invention will appear in the following description of the preferred embodiment of the invention shown 40 in the attached drawings, of which:
- Figure 1 is a plan view of the clutch mechanism;
- Figure 2 is a plan view of the clutch mechanism with the top cover and solenoid brake mechanism removed;
- Figure 3 is a vertical cross section taken on lines 3—3 of Fig. 1;
- Figure 4 is schematic diagram of the electrical connections and apparatus;
- 50 Figure 5 is a detail of a clutch shifter lever;
- Figure 6 is a detail view in vertical section of the clutch shifter lever bearing;
- Figure 7 is an elevation of the solenoid operated brake mechanism; and
- Figure 8 is a detail of one of the gears of the clutch mechanism on a reduced scale.
- Referring more particularly to the drawings, 5 **10** indicates the clutch mechanism housing which comprises a base member **11** and a cover member **12**. The base member **11** is provided with four half bearings **13** to receive a pair of shafts **14** and **15** extending laterally through the housing. Similarly the cover member **12** is provided with half bearings **16** which cooperate with the half bearings **13** to form journals for the shafts **14** and **15** when the cover **12** is in position. Shaft **14** is provided with a gear **17** loosely journaled upon the shaft **14** between a friction clutch disc **18** rigidly mounted upon the shaft **15** **10** and a friction clutch disc **19** mounted upon the shaft **14** so as to be slidable axially thereof. The clutch disc **19** is provided with a hub portion **20** which is caused to rotate with the shaft by means of a key **21**. Also the shaft **14** may be provided with a thrust collar **22** fixed thereto to prevent longitudinal movement thereof. It will be seen that forcing the disc **19** axially of the shaft **14** against the gear **17** will cause the said gear to be frictionally engaged between the **25** discs **18** and **19** so as to rotate with the shaft **14**.
- The shaft **15** is also provided with a gear **23** which meshes with the gear **17** and which is positioned between friction clutch discs **24** and **25** which are exactly similar to the discs **18** and **19** upon the shaft **14**, and are similarly mounted upon the shaft **15**. The shaft **15** may also be provided with a thrust collar **22** exactly similar to the thrust collar upon the shaft **14**. The gears **17** and **23** and the clutch discs **18**, **19**, **24** **30** and **25** run in oil contained in the housing **10** and as shown in Fig. 8, the gear **17** is provided with curved slots **25a** cut entirely through the gear and extending outwardly from a point adjacent the center of the gear beyond the outer **35** peripheries of the clutch discs **18** and **19** as shown in Fig. 3. The slots **25a** pick up oil from the housing **10** and deliver it to the friction surfaces between the gear **17** and the discs **18** and **19**. The gear **23** is also provided with similar **40** slots (not shown) for the purpose of supplying oil to the friction surfaces between the gear **23** and clutch discs **24** and **25**.
- The two clutch discs **19** and **25** are shifted to engage and disengage the gears **17** and **23** respectively by a solenoid **26** mounted upon a bracket **27** carried by the cover member **12**. The plunger **28** influenced by the solenoid **26** is provided with a rod **29** extending through an aperture **30** in the upper end of a shifter lever **31** **45** **50** **55**

extending downwardly through the cover member 12 and journalled at 32 in said cover member. As shown in Figure 5, the shifter lever 31 is provided with a pivot 33 extending therethrough which is positioned in the bearing 32 formed partly in the cover member 12 and a bearing plate 35 bolted thereto. The lower end of the shifter lever 31 terminates in a fork 36 provided with lugs 37 which engage an annular groove 38 in the hub 20 of clutch disc 19.

The solenoid plunger rod 29 is provided with a collar 38a fixed thereto which bears against one side of the shifter lever 31. A compression spring 39 is positioned between the collar 38a and a washer 40 carried by the solenoid bracket 27. The solenoid plunger rod 29 also extends through an aperture 41 in a rocker lever 42 journalled at 43 upon the top surface of the cover member 12. A compression spring 44 is positioned between the shifter lever 31 and the rocker lever 42. A nut 45 is screw threaded upon the extreme end of the solenoid plunger rod 29 to maintain said springs under compression.

The clutch disc 25 is also actuated by a shifter lever 56 (Fig. 1) provided with lugs 37 engaging an annular groove 57 (Fig. 2) upon the hub of the clutch disc 25. A shifter rod 57 extends through an aperture in the upper end of the shifter lever 56, through an aperture in a stationary abutment 58 upon the upper surface of the cover member 12 and an aperture in the end of the rocker lever 42 remote from the solenoid plunger rod 29. A compression spring 59 is positioned between the shifter lever 56 and the abutment 58. The shifter rod 57 is provided with an adjusting nut 60 screw-threaded upon one end thereof to be engaged by the rocker 42 during the operation of the device.

The shafts 14 and 15 extend beyond one side of the clutch mechanism housing 10 and are provided with pulleys 61 and 62. The shaft 15 is also extended outwardly from the other side of the clutch mechanism housing 10 and is provided with a brake drum 63 to receive a solenoid operated brake more clearly shown in Figs. 1 and 7. The brake includes a brake band 64 resiliently secured to a bracket 65 secured to the base member 11 of the clutch mechanism housing. A spring 66 carried by an operating rod 67 extending through brackets 68 and 69 carried by the opposed ends of the brake band 64 urges the brake band toward tightened position. The brake is released by a solenoid 70 mounted upon the bracket 65 by means of a bell crank 71 journalled in the bracket 68 and connected to the bracket 69 by compression links 72.

The operation of the device thus far will now be described. The clutch disc 19 is normally held in disengaged position by means of the spring 39 operating through the shifter lever 31. The clutch disc 25 is normally held in engaged position by means of the spring 59 operating through the shifter lever 56. Upon energization of the solenoid 26 the solenoid plunger 28 is pulled to the left in Fig. 3 to compress the spring 39 and rock the shifter lever 31 anti-clockwise in Fig. 3 through spring 44. The spring 44 is of greater strength than the spring 39 but is normally prevented from maintaining the clutch disc 19 in engaged position by reason of the collar 38a fixed upon the solenoid plunger rod 29. This movement of the solenoid plunger rod 29 rocks the rocker lever 42 about its pivot

63 in a clockwise direction in Fig. 1 to bring the opposite end of the rocker lever 42 adjacent the nut 60 upon the shifter rod 57. The engagement of clutch disc 19 with the gear 17 prevents further movement thereof. Further movement of the solenoid plunger 28 toward the left in Fig. 3 by reason of an increase in the energization of the solenoid 26 acts to compress the spring 44 and further rock the lever 42 in a clockwise direction in Fig. 1. The lever 42 10 engages the nut 60 upon the shifter rod 57 to compress the spring 59 and rock the shifter lever 56 to allow slipping between the clutch disc 25 and the gear 23. It will thus be seen that energization of the solenoid 26 first causes 15 the engagement of the clutch disc 19 with the gear 17 and that further energization of the solenoid 26 will cause slipping between the clutch disc 25 and the gear 23.

In Fig. 4 is shown a schematic diagram of 20 the electrical apparatus which operates the various clutches and solenoid brake heretofore described. In this figure a main motor 73 drives a mill such as a flour or feed mill (not shown) by means of the belt 74 and is connected to a 25 source of electrical power 75 through a manually operable switch or starter 76. A feed motor 77 drives the shaft 14 of the clutch mechanism through a belt 78 and a feed mechanism (not shown) is driven by a belt 79 engaging pulley 30 82 mounted upon shaft 15.

The motors 73 and 77 are connected through the switch 76 to the line 75 by conductors 80, 81 and 82, and may operate upon either alternating or direct current. The conductor 82 is 35 connected to the switch 76 by conductors 83 and 84 through an automatic feed control solenoid 85. Although two motors are shown, it is obvious that both the mill and the feed mechanism may be driven from a single motor if the arrangement of these machines is such as to make this practical. A contact making voltmeter 86 provided with a dash-pot 87 is connected across conductors 80 and 82 and is provided with a moving contact 88 and a stationary contact 89 45 to close a circuit through a relay 90 also connected across conductors 80 and 82 in series with contacts 88 and 89 so as to cause the relay 90 to operate after a time delay. Energization of the relay 90 closes contacts 91 and 92 thereof 50 to connect the clutch operating solenoid 26 and the brake operating solenoid 70 in parallel with automatic feed control solenoid 85 and in series with the manually operable rheostat 94 and the automatic control rheostat 95. This circuit may 55 be traced from conductor 83, through manually operable rheostat 94, automatic control rheostat 95, contacts 91 and 92 of the relay 90 through solenoids 26 and 70 in parallel and back to conductor 84. The rheostat 94 may be operated 60 manually to control the amount of current flowing through clutch operating solenoid 26 and brake operating solenoid 70 and a further automatic control of this current is provided by the rheostat 95 operated by the solenoid 85 by means 65 of a solenoid plunger 97 pivotally connected at 98 to a contact lever 99 which is pivoted at 100. The solenoid plunger 97 is provided with a dash-pot 101 and the contact lever 99 is returned by a spring 102. An adjustable stop which may be 70 an adjusting screw 103 screw-threaded through a stationary member 104 and bearing against the contact lever 99 serves to adjustably limit the upward movement of the contact lever 99.

In the operation of the device, when the switch 75

78 is closed, the motors 73 and 77 start but since the clutch disc 19 is disengaged from the gear 17 the feed mechanism is not driven while the motors are coming up to speed. This is true 5 since the relay 90 is open and the solenoid 26 is not energized. Also when the switch 76 is closed, voltage is impressed across the contact-making voltmeter 86. The contacts 88 and 89, however, are not closed until after a time delay because 10 of the dash-pot 87. In practice the dash-pot 87 is adjusted so that the contacts 88 and 89 are not closed until the mill motor 73 has come up to speed. As soon as contacts 88 and 89 are 15 closed by the contact-making voltmeter 86, relay 90 is energized to close contacts 91 and 92 to energize clutch operating solenoid 26 through the manually operable rheostat 94 and the automatically operable rheostat 95. At this time the load current on the motor 73 has reached or 20 is less than its normal operating value depending upon the amount of material in the mill and in operation the rheostat 94 is adjusted so that sufficient current flows through the solenoid 26 to engage clutch disc 19 with the gear 17 and 25 slight slipping of the gear 23 relative to clutch disc 25.

Also when contacts 91 and 92 are closed brake operating solenoid 70 is energized to release the brake 64 and upon engagement of clutch disc 19 with gear 17 the feed mechanism is driven by belt 79 through clutch gear 23 and clutch discs 24 and 25. At this stage both the mill and the feed mechanism are being driven at their normal speeds. If the load current of the motor 73 increases above the normal value due to too much material in the mill or other causes, the current through clutch solenoid 26, which is connected in series with the motor 73 and in parallel with automatic control solenoid 85, increases 30 to disengage clutch disc 25 from gear 23 to a greater extent to allow the feed mechanism to slow down or even stop. The current through clutch solenoid 26 is prevented from increasing as fast as the motor current by the automatic 35 control rheostat 95 which is operated to cut in resistance by the automatic control solenoid 85 when the motor current increases. When the load current on motor 73 again drops toward normal value, the current through clutch solenoid 26 decreases to allow tighter engagement 40 of clutch disc 25 with gear 23 to again drive the feed at normal speed. The decrease in current through solenoid 26 is partially compensated by the operation of automatic control 45 solenoid 85 operating to cut out resistance in rheostat 95. Thus the control solenoid 85, in conjunction with clutch solenoid 26, is effective to maintain the load current on the motor 73 at a predetermined value as shown by the ammeter 50 93. The desired predetermined value of load current on motor 73 may be selected by adjusting manually operable rheostat 94 to adjust the amount of current flowing through clutch operating solenoid 26. The adjustable stop screw 55 103 bearing against contact lever 99 determines the maximum value of motor current. When the lever 99 engages screw 103, the increase in current through clutch solenoid becomes proportional to the increase of motor current and an 60 increase of motor current above that necessary to cause engagement of lever 99 with screw 103 will cause rapid disengagement of clutch disc 65 25 from gear 23 to stop the feed since any further compensation by rheostat 95 is prevented. 70 When the switch 76 is open to stop the motor or 75

power fails for any other reason, the contacts 88 and 89 of the voltmeter 86 immediately disengage, which permits contacts 91 and 92 of the relay 90 to disengage, the clutch operating solenoid 26 and the brake operating solenoid 70 5 are immediately deenergized to disengage clutch disc 19 and gear 17 and the feed is immediately stopped by the brake 64. The brake operating solenoid 70 is subjected to the same variations in current as clutch operating solenoid 26 but the 10 current through solenoid 70 is always sufficient to maintain the brake released when contacts 91 and 92 are closed.

While I have herein disclosed the preferred embodiment of my invention, it is to be understood that the precise structure disclosed may be modified within the scope of the appended claims.

Having thus described my invention, I claim:

1. In a device for controlling the rate of feed 20 to a mill or the like, an electric motor for driving said mill, means for driving a feed mechanism for feeding material to said mill, a friction clutch mechanism between said means and said feed mechanism, said means being disconnected from 25 said feed mechanism by said clutch mechanism when said motor is not connected to a source of power, means for connecting said motor to said source of power, means for operating said clutch mechanism to cause said driving means to drive 30 said feed mechanism after said motor has been connected to said source of power and means responsive to the load on said motor for causing operation of said clutch mechanism to decrease the rate of feed when said load increases and to 35 increase the rate of feed when said load decreases.

2. In a device for controlling the rate of feed 40 to a mill or the like, an electric motor for driving said mill, means for driving a feed mechanism for feeding material to said mill, a friction clutch mechanism between said means and said feed mechanism, said means being disconnected from 45 said feed mechanism by said clutch mechanism when said motor is not connected to a source of power means for connecting said motor to said source of power, electrical means for operating said clutch mechanism to cause said driving means to drive said feed mechanism after said motor has been connected to said source of power 50 and electrical means responsive to the load current taken by said motor for causing operation of said clutch mechanism to decrease the rate of feed when said load increases and to increase the rate of feed when said load decreases. 55

3. In a device for controlling the rate of feed 60 to a mill or the like, an electric motor for driving said mill, means for driving a feed mechanism for feeding material to said mill, a friction clutch mechanism between said means and said feed mechanism, said means being disconnected from 65 said feed mechanism by said clutch mechanism when said motor is not connected to a source of power, means for connecting said motor to said source of power, electrical means for operating said clutch mechanism to cause said driving means to drive said feed mechanism, a time delay device for initiating the operation of said clutch operating means after said motor has been connected to said source of power and electrical 70 means responsive to the load current taken by said motor for causing operation of said clutch mechanism to decrease the rate of feed when said load increases and to increase the rate of feed when said load decreases. 75

4. A device for controlling the rate of feed to a mill driven by an electric motor comprising, means for driving a feed mechanism for feeding material to said mill, a friction clutch mechanism between said means and said feeding mechanism including a pair of clutches, means for connecting said motor to a source of power, one of said clutches being disengaged when said motor is disconnected from said source of power, and electrical means for engaging said last mentioned clutch after said motor is connected to said source of power, the other of said clutches being normally engaged, said electrical means including means responsive to the load current taken by said motor for causing at least partial disengagement of said other clutch when said load current exceeds a predetermined value.
5. A device for controlling the rate of feed to a mill driven by an electric motor comprising, means for driving a feed mechanism for feeding material to said mill, a friction clutch mechanism between said means and said feeding mechanism including a pair of clutches, means for connecting said motor to a source of power, one of said clutches being disengaged when said motor is disconnected from said source of power, electrical means for engaging said last mentioned clutch after said motor is connected to said source of power, the other of said clutches being normally engaged, said electrical means being responsive to the load current taken by said motor for causing at least partial disengagement of said other clutch when said load current exceeds a predetermined value, and manually operable means for adjusting said predetermined value of load current.
6. In a device for controlling the rate of feed to a mill or the like, means for driving a feeding mechanism for feeding material to said mill, a friction clutch mechanism between said means and said feeding mechanism including a pair of friction clutches, one of said clutches being normally engaged and the other of said clutches being normally disengaged, a single solenoid for operating both said clutches, means for energizing said solenoid for engaging said normally disengaged clutch and means for increasing the energization of said solenoid to at least partially disengage said normally engaged clutch.
7. In a device for controlling the rate of feed to a mill or the like having an electric motor driving a feeding mechanism for feeding material to said mill, said device comprising a pair of shafts, one of said shafts being driven by said feed mechanism driving means and having a gear loosely journaled thereon, the other of said shafts driving said feeding mechanism, and having a gear loosely journaled thereon and meshing with said first named gear, independently operable clutches for clutching said gears to said shafts for rotation therewith, one of

said clutches being normally engaged and the other of said clutches being normally disengaged, a single solenoid for operating both said clutches, means for connecting said motor to a source of electrical power, means including a contact making voltmeter actuated by the voltage impressed upon said motor and a time delay device for energizing said solenoid at a predetermined time after said motor is connected to said source of power to engage said normally disengaging clutch, magnetically operated means responsive to the load current taken by said motor for increasing the energization of said solenoid to at least partially disengage said normally engaged clutch upon increase of said load current above a predetermined value, manually controlled means for predetermining said value of said load current, means for returning said clutches to normal position when said motor is disconnected from said source of power, means for applying a brake to the shaft driving said feeding mechanism when said motor is disconnected and means for releasing said brake when said motor is connected to said source of power.

8. In a device for controlling the rate of feed to a mill or the like driven by an electric motor, means for driving a feed mechanism for feeding material to said mill, solenoid operated means responsive to changes in load current to said motor for controlling said feed mechanism driving means to control rate of feed to said mill, a solenoid connected in series with said motor for operating said solenoid operated means, a variable resistance connected in series with said solenoid and an automatic control solenoid connected in series with said motor for varying said resistance to reduce the change in the current through said first named solenoid due to changes in said motor current.

9. In a device for controlling the rate of feed to a mill or the like driven by an electric motor, means for driving a feed mechanism for feeding material to said mill, solenoid operated means for controlling said feed mechanism driving means to control the rate of feed to said mill, a solenoid connected in series with said motor for operating said solenoid operated means to decrease said rate of feed upon an increase of motor current, a variable resistance connected in series with said solenoid, an automatic control solenoid for increasing the resistance of said variable resistance upon an increase of motor current to partially prevent an increase in the current through said first named solenoid due to an increase in motor current and an adjustable means for preventing further operation of said automatic control solenoid to increase said resistance when said motor current reaches a predetermined maximum value.

CLARENCE J. HESS.
